UNITED STATES PATENT OFFICE.

THOMAS PODMORE, OF WILKESBARRE, PENNSYLVANIA.

BUILDING-BLOCK.

SPECIFICATION forming part of Letters Patent No. 772,476, dated October 18, 1904.

Application filed April 21, 1904. Serial No. 204,273. (No model.)

To all whom it may concern:

Be it known that I, THOMAS PODMORE, a citizen of the United States, residing at Wilkes-barre, in the county of Luzerne and State of Pennsylvania, have invented a new and useful Building-Block, of which the following is a specification.

This invention relates to an artificial-stone building-block and method of making the same.

The object of the invention is to provide an artificial stone for building purposes having a veneer or exterior finish in imitation of marble, granite, and similar natural rocks.

The invention consists in applying to the surface of the molded block a thin layer of cement and while the latter is still in a plastic condition sifting a quantity of marble, granite, or similar stone screenings thereon, the surface of the stone after the cement has thoroughly set or solidified being rubbed or polished to remove any loose particles or irregularities in the face of the block, and thereby produce an exterior finish resembling cross-cut or chiseled natural rock.

In the accompanying drawings, forming a part of this specification, Figure 1 is a perspective view of a building-block constructed in accordance with my invention. Fig. 2 is a longitudinal sectional view of the block before applying the exterior finish. Fig. 3 is a similar view showing the screenings on the face of the block. Fig. 4 is a longitudinal sectional view of Fig. 1.

Similar numerals of reference indicate corresponding parts in all the figures of the drawings.

The block 5, which may be formed of a mixture of cement and sand or other suitable material molded into the desired shape, is provided with a thin layer of cement 6, on which is sprinkled a quantity of marble, granite, or similar stone screenings 7, the latter being subsequently rubbed or ground to produce the imitation-stone veneer or exterior finish, (indicated at 8 in Fig. 1 of the drawings.)

In carrying out the invention I place the blocks 5 after they are thoroughly dry on a conveyer or traveling platform and pass the same under a receptacle containing cement, a thin layer of which is deposited on the face of the blocks. The blocks are then passed beneath a vibrating screen and a quantity of marble or granite screenings or similar granular material sifted over the cemented face of the blocks, and thence beneath a tamp which firmly presses or embeds the screenings in said cement. The blocks are then placed in the drying-room, and after the cement has thoroughly set or solidified the surface of the blocks are rubbed or ground with a stiff brush or stone to remove any loose particles and irregularities on the face of the same, thereby producing an exterior finish or veneer resembling cross-cut or chiseled natural rock, as illustrated in Fig. 1 of the drawings.

It is obvious that the veneer may be applied to the blocks either before or after the latter are molded, and it is also obvious that any suitable granular material may be deposited on the surface of the block instead of the marble and granite screenings shown and described.

Having thus described the invention, what is claimed is—

The method of veneering artificial stone which consists in depositing a layer of cement on the face of the block, sprinkling granular material thereon, tamping said granular material, and finally smoothing the surface of the block by rubbing or grinding the exposed granules so as to present a raised rock face in imitation of cross-cut or chiseled stone.

In testimony that I claim the foregoing as my own I have hereto affixed my signature in the presence of two witnesses.

THOMAS PODMORE.
